United States Patent Office.

JACOB MILLER, OF CARROLLTON, OHIO.

Letters Patent No. 70,103, dated October 22, 1867.

IMPROVED CAR-COUPING.

The Schedule referred to in these Letters Patent and making part of the same.

TO ALL WHOM IT MAY CONCERN:

Be it known that I, JACOB MILLER, of Carrollton, in the county of Carroll, and State of Ohio, have made new and useful improvements in Car-Couplings; and I do hereby declare the following to be a full and correct description of the same, sufficient to enable others skilled in the art to which my invention appertains to understand and use the same, reference being had to the accompanying drawings, which make part of this specification, and in which—

Figures 1 and 2 are sectional side elevations of my improved coupling device.

Similar letters of reference indicate corresponding parts in the two figures.

My invention relates to an improvement on a coupling device for which I have made application for Letters Patent already, and consists in the use of a spring-tumbler, which always rests on the coupling-link, and keeps the latter in a horizontal position, and over the projection or hook when the coupling is effected.

A in the drawing may represent the draw-head of a car, provided with an internal chamber to hold the coupling devices, which consist of the stationary hook or catch B, projecting backward and upward from the bottom of the draw-head, the tumbler C, pivoted at c, and acted upon by the plunger D, which is forced downward by the spring within the cylinder or casing D', and the cheek-pieces C' and pin c', which is pivoted at d, and operated by the lever E. The coupling-link F in this case may be the one commonly used. When the same is introduced into the mouth of the draw-head A, and passes over the inclined plane of the catch B, it raises at the same time the pivoted tumbler C, and, as soon as it has passed in sufficiently for the loop to pass over the rear point of the catch B, it falls downward, and rests on the pin c', the tumbler C pressing down on it, keeping it in a horizontal position, and preventing its passing over the catch B.

To withdraw the link F from the draw-head, the lever E is moved forward, and the link F is thereby raised above the catch B. The same movement raises the tumbler C, resting on the link F, while the latter is lifted to a sufficient height to allow it to pass out clear of the catch B.

The movable frame G, operated by the spring-plunger H, is precisely the same as described in my previous application, and needs no further description.

Having thus described my invention, what I claim as new therein, and desire to secure by Letters Patent, is—

1. In the above-described coupling device, the pivoted tumbler C, acting independently from the cheek-pieces C', substantially as and for the purposes set forth.
2. The combination of the pivoted tumbler C, spring-plunger D, cheek-pieces C', provided with lever E and pin c' and the movable frame G, acted upon by the spring-plunger H, substantially as and for the purposes described.
